UNITED STATES PATENT OFFICE.

ORVIS NELSON, OF MINNEAPOLIS, MINNESOTA.

GRAIN-CAR DOOR.

No. 895,036.

Specification of Letters Patent.

Patented Aug. 4, 1908.

Application filed March 14, 1906. Serial No. 306,090.

To all whom it may concern:

Be it known that I, ORVIS NELSON, a citizen of the United States, residing at Minneapolis, in the county of Hennepin and State 5 of Minnesota, have invented a new and useful Grain-Car Door, of which the following is a specification.

This invention relates to grain-car doors, and has for its object to provide a door capable of being adjusted vertically and also swung laterally within the car to elevated position to facilitate the introduction and removal of the grain or other contents of the car.

15 A further object of the invention is to provide improved means for locking the door, and means for moving the latter to operative position.

A further object of the invention is to generally improve this class of devices so as to add to their utility and durability as well as to reduce the cost of manufacture.

With these and other objects in view the invention consists in the construction and 25 novel combination and arrangement of parts hereinafter fully described, illustrated in the accompanying drawings and pointed out in the claims hereto appended.

In the accompanying drawings forming a 30 part of this specification:—Figure 1 is a longitudinal sectional view of the interior of a grain-car showing my improved door in position thereon. Fig. 2 is a side elevation of a portion of the exterior of the car. Fig. 3 is a 35 transverse sectional view. Fig. 4 is a detail transverse sectional view of the locking mechanism. Fig. 5 is a similar view of a portion of the grain-door and the adjacent post or standard. Fig. 6 is a side elevation of a 40 hook for supporting the grain-doors in elevated position.

Similar numerals of reference indicate corresponding parts in all of the figures of the drawings.

45 The improved door may be used in connection with different kinds of cars and by way of illustration is shown applied to a grain-car of the ordinary construction in which 5 designates the body of the car provided with 50 spaced side posts or jambs 6, defining a door receiving opening 7. Disposed within the opening 7 is a vertically sliding door 8, the opposite edges of which are provided with reinforcing members or plates 9 each having an 55 extension 10 adapted to bear against the inner face of the adjacent side post as shown,

there being suitable rollers 11 journaled in the plates 9 at the upper and lower ends of the door for engagement with a wear-plate 12, fastened in any suitable manner to said 60 posts. Secured to the inner face of the door 8 is a circular plate or disk 13 provided with a cylindrical extension 14 journaled in a socket or bushing 15 secured to the outer face of said door and to which is keyed or otherwise rigidly secured a hand operated lever 16.

Eccentrically mounted on the plate 13 by means of suitable pivoted pins 17 are links 18 to which are secured links 19, the latter being pivotally connected at 20, to locking bars or 70 bolts 21 slidably mounted for longitudinal movement in suitable guides 22 and adapted to engage keepers 23 fastened to side posts or jambs as shown.

Secured to the side posts 6 and preferably 75 spaced inwardly from the opening 7 are vertical guide-rods 24 which engage eyes or loops 25 extending laterally from clips or brackets 26 secured to the upper edge of the door. The upper ends of the guide-rods 24 80 are preferably bent laterally to form loops 27 adapted to receive the eyes 25 when the door is adjusted vertically and swung inwardly to the elevated position shown in Fig. 3 of the drawings, said doors being locked in elevated 85 position by means of hooks 28 depending from the top of the car and engaging the adjacent edges of the doors as shown.

As a means for moving the door to elevated 90 position suitable cords or cables 29 are secured to the upper edge of the door and thence pass over rollers or pulleys 29' to a drum or reel 30 mounted for rotation on one of the posts or jambs 6. The drum is rotated to elevate the door by means of a handle 31 provided with a spring ratchet tooth 32 adapted to engage the ratchet teeth on the drum as the handle is rotated, backward movement of the ratchet-wheel 33 being prevented by a suitable locking pawl 34.

100 The hand operated lever 16 is provided with a locking tooth 35 adapted to engage the notches or teeth of a segmental rack 36 secured to the outer face of the door 8 so that the bolts 21 may be locked in either operative or inoperative position.

105 In operation when it is desired to release the door, the handle 16 is rotated in one direction which causes the levers 18 to exert a longitudinal pull on the links 19 and thereby 110 withdraw the bolts 21 from the keepers 23. The door may then be elevated above the

floor of the car by rotating the handle 31 to wind the cord 29 on the drum 30.

When it is desired to support the doors in elevated or inoperative position, said doors are adjusted vertically until the eyes 25 engage the loops 27, the doors being then swung inwardly and upwardly into engagement with the pivoted hook 28.

Secured to the door near the bottom there is a bracket or cleat 37 adapted to receive the point of a cross-bar or similar tool to assist in elevating the door when the pressure of the grain is excessive or when frost or snow causes the door to stick.

Attention is called to the fact that the doors 8 are preferably of such a height that when the same are swung upwardly to inoperative position the free ends of the doors will over-lap and thus permit a single hook or other fastening device 28 to retain the doors in elevated position. It will of course be understood that either or both of said doors may be elevated, the hook being so disposed that the bill thereof will engage one edge of either door as shown.

By having the locking bolts secured to the rotating disk or plate 13 in the manner described, said bolts may be simultaneously moved to operative and inoperative positions, the construction and relative disposition of the several levers and connecting links being such as to permit the operation of the bolts with a minimum expenditure of the power.

Having thus described the invention what is claimed is:—

The combination with a car including spaced posts forming a door receiving opening, wear plates secured to the inner faces of the posts, a door slidably mounted for vertical movement between the wear plates and formed of a plurality of superposed transverse strips, substantially rectangular casings secured to the vertical edges of the door and forming housings for the opposite ends of the transverse strips and each provided with a laterally extending flange forming a continuation of one side of the casing and adapted to bear against the longitudinal edge of the adjacent wear plate at the inside of the car, a keeper secured to the inner face of each post in spaced relation to the adjacent wear plate, keepers secured to the casings and disposed in horizontal alinement with the keepers on the posts, locking members slidably mounted on the door and adapted to engage the keepers on the casings and posts, respectively, for forcing the flanges of said casings in engagement with the adjacent wear plates, means for elevating the door, and means for supporting the door in elevated position.

In testimony that I claim the foregoing as my own, I have hereto affixed my signature in the presence of two witnesses.

ORVIS NELSON.
